UNITED STATES PATENT OFFICE.

FRANÇOIS JULES CHAPSAL AND ALFRED LOUIS EMILE SAILLOT, OF PARIS, FRANCE.

PNEUMATIC BRAKE FOR GOODS-TRAINS.

No. 802,913.

Specification of Letters Patent.

Patented Oct. 24, 1905.

Application filed December 28, 1904. Serial No. 238,648.

To all whom it may concern:

Be it known that we, FRANÇOIS JULES CHAPSAL and ALFRED LOUIS EMILE SAILLOT, engineers, citizens of the Republic of France, residing at Paris, France, (whose post-office address is 37 Rue St. Petersbourg, Paris,) have invented a new and useful Pneumatic Brake for Goods-Trains, (for which we have obtained a French patent, December 26, 1903, not yet issued,) of which the following is a specification.

This invention has for its object a brake-distributer composed of two coördinated parts, which by acting in combination insure the regulation of the admission and the discharge of the air to and from the brake-cylinders. The first of these parts, which is termed the "distributing-valve," comprises a special slide controlled by an ordinary piston. By itself it is incapable of insuring either the admission or the discharge of the air to and from the brake-cylinder; but it is constituted for: (a) insuring during the intervals between the applications of the brakes, on the one hand, the simultaneous supply of air from the train-pipe to two different reservoirs, one of which is termed the "regulating-reservoir" and regulates the operation of the apparatus, while the other is called the "braking-reservoir" and serves wholly to furnish the air to the brake-cylinder and the placing in communication of the brake-cylinder and chambers of the second part with the outer air; (b) immediately before the beginning and until the absolute termination of each braking, to interrupt the mutual relationship between the two reservoirs, cut off both of them from the train-pipe, and effect the connection of the chambers of the second part already referred to, as to one of them with the regulating-reservoir and as to the other with the train-pipe. The second part, termed the "braking-regulator," comprises the ordinary arrangement of three diaphragms or pistons of different diameters mounted upon the same spindle. Under the influence of the difference of pressure between the regulating-reservoir and the train-pipe these parts control the ordinary valve regulating the admission of air from the braking-reservoir into the brake-cylinder and also a second valve regulating the graduated discharge of the air from this same braking-cylinder into the atmosphere.

A constructional form of this brake is represented, by way of example, in the accompanying drawings, in which—

Figure 1 shows the brake as a whole as far as concerns one vehicle, and Figs. 2 and 3 illustrate the action of the slide of the distributing-valve.

The brake represented in Fig. 1 comprises for each vehicle a train-pipe A, the extremity of which terminates in ordinary couplings, a distributer B, a brake-cylinder C, comprising one or two pistons, an air-reservoir G, and a braking-reservoir H.

The distributing-valve B presents, Fig. 1, two chambers 1 and 2. In the chamber 1 is mounted a piston α , one of the faces of which acts as a valve relatively to the chamber 2. Its rod carries a slide-valve b . The chamber 1 is in communication, through a conduit c and the branch E, with a regulator D, interposed on the train-pipe A. It also communicates, by means of a conduit d , with the distributing-valve face over which the slide b moves. The chamber 2 is in communication with the air-reservoir G by means of a pipe e and with the reservoir H by a conduit f , which comprises a branch opening into the regulators. The conduits d and f both open on the face for the slide-valve b , which face also presents four other orifices g h i z , the first two and the fourth establishing communication with the braking-regulator and the third opening into the atmosphere. The valve b is caused to bear against the valve-face by a spring and is provided with a cavity, which is hereinafter referred to. Incisions are formed at j and k , respectively in the chamber 1 and in the chamber 2, which are likewise united in the position of the distributer-piston represented in the figure by the intermediary of a non-return valve M, serving to facilitate the admission of air to the chamber 2.

The braking-regulator is subdivided, Fig. 1, into four compartments 3 4 5 6 by means of three flexible diaphragms l , m , and n , which are fixed at their center to one and the same rod σ . The conduit h , referred to above, opens into the compartment 3, the conduit g opens into the compartment 6, and that terminating at z into the compartment 4. The compartment 5 is likewise provided with an aperture p , opening into the atmosphere. The compartment 4 is in communication through the

FLUID PRESSURE BRAKE & ANALOGOUS SYSTEMS.

pipe J with the brake-cylinder C. This latter compartment is provided with two independent chambers *q* and *r*, in which are respectively the valves *s* and *t*. These valves comprise rods bearing, respectively, upon the arms *u* and *v* of a part rocking at *w*, a third arm of which engages with the said rod *o*. The branch of the conduit *f* opens into the chamber *q*. The valve *t* is submitted to the action of a spring *x*, and the chamber which comprises it opens externally by means of an aperture *y*. K is a blow-through valve.

1. The train being running, the air of the train-pipe A enters the distributor B, through the conduit *c* beneath the piston *a* and maintains it at the highest point of its stroke. This air flows into the chamber 2 on the one hand through the incisions *j* and *k* and on the other through the non-return valve M, proceeding through the conduit *e*, which is always open, into the air-reservoir G, and also through the conduit *f* into the braking-reservoir H. The two reservoirs, united by a non-return valve N, are therefore supplied with air at the pressure of the train-pipe A. The brake-cylinder C is in constant communication with the chamber 4 of the moderator, which *is* hereinafter explained, is free from air when the piston *a* is at the highest point of its stroke. Under these conditions the brakes are released.

2. In order to apply the brakes, the pressure is reduced in the pipe A. When the pressure has been sufficiently reduced, the piston *a* descends to its lowest point by reason of the difference of pressure between the air of the regulating-reservoir G and the air in the conduit A. The displaced slide-valve *b* assumes the position indicated diagrammatically in Fig. 3. At this moment the conduit *f* is obturated; but the air of the braking-reservoir H still passes through the branch of this conduit above the valve *s*. The orifice *i* is obturated, as is also the orifice *z*. The orifice *g* is then open, and the air of the regulating-reservoir G then reaches the chamber 6 of the moderator, which is of very small capacity. The conduits *d* and *h* are in communication through the cavity of the slide-valve *b*, and the air of the train-pipe A enters the chamber 3 of the moderator. When the conditions are as above set forth, the chamber of the moderator receives the air of the conduit A, which has decreased in pressure, while the chamber 6 fills with air coming from the regulating-reservoir G, which has preserved its pressure. The three diaphragms yield toward the left hand, and the arm *u* lifts the valve *s*. The air of the braking-reservoir H enters the chamber 4 and thence through the pipe J reaches the brake-cylinder C. The brakes are therefore applied, and as the diaphragm *m* is larger than the diaphragm *l* equilibrium is soon reestablished for a predetermined diminution of pressure, and when the braking-reservoir has furnished the desired pressure

to the brake-cylinder the diaphragms return to their position of equilibrium and the valve *s* closes.

3. If in the course of the stoppage the air-supply of the train-pipe A is replenished, the equilibrium of the diaphragm is again disturbed, but in the opposite direction. They move toward the right hand, and the valve *t* is lifted, so that a partial escape takes place of the air of the brake-cylinder C through the orifice *y*, and the application of the brake is lessened. The importance of this arrangement will be apparent, as it permits of beginning the release of the brakes as soon as the train-pipe is recharged, and consequently of reducing the application of the brake-shoes at will without modifying the position of the slide-valve of the distributor, and therefore without passing through the total-release stage.

4. In order to completely release the brakes, air is sent into the train-pipe A in such a manner as to reestablish the pressure which preceded their application. Before this pressure is reached the diaphragms, the equilibrium of which is disturbed by the increase of pressure in 3, will have opened the air-discharge valve *t*, the air of the brake-cylinder C will have escaped progressively, and the release will have taken place gradually. When the initial pressure is reestablished in the conduit A—that is to say, at the moment at which the movement of the piston of the distributor takes place—the brake is already released. The piston *a* then rises and returns to the position shown in Fig. 1. The chambers 3, 4, and 6 of the moderator are again placed in communication with the atmosphere by the slide-valve *b*, and the diaphragms are no longer submitted to the action of the compressed air, whereby their wear is considerably reduced, as it is only during braking that they are under pressure.

It has been shown that the braking-reservoir exerts no influence upon the operation of the distributor, (which depends only upon the regulating-reservoir.) It may therefore be made of as large a size as permitted of by practical considerations of mounting, weight, &c.

We claim as our invention—

1. In an air-brake mechanism, a distributor composed of a distributing-valve in connection with the air-supply, a braking-regulator in connection with the braking-cylinder, reservoirs in communication with said valve and braking-regulator, and a valve communicating between said reservoirs.

2. In an air-brake mechanism, a distributor composed of a distributing-valve in connection with the air-supply, a braking-regulator in connection with the braking-cylinder, and reservoirs in communication with said valve and said braking-regulator, said distributing-valve comprising a cylinder, a piston therein,

a slide-valve on the piston-rod and a separate valve to control the air-supply to one of said reservoirs through said cylinder.

3. In an air-braking mechanism, a distributor composed of a distributing-valve in connection with a braking-regulator, said distributing-valve comprising a cylinder, a piston therein and a slide valve on the piston-rod, and said braking-regulator comprising 5 a plurality of compartments, flexible diaphragms between said compartments, and one

of said compartments in communication with the atmosphere through said slide-valve.

In testimony whereof we have signed our names to this specification in the presence of 15 two subscribing witnesses.
